His ATTORNEY.

UNITED STATES PATENT OFFICE

2,470,933

FLEXIBLE-SURFACED BONE CONDUCTION
HEARING AID UNITHugh S. Knowles, River Forest, Ill., assignor to
Zenith Radio Corporation, a corporation of
Illinois

Application June 5, 1944, Serial No. 538,309

Claims. (Cl. 179—107)

1

This invention relates to hearing aid earphones of the "bone conduction" type having a vibratile element arranged to transmit vibrations to the auditory nerve through the bony structure of the head of a user.

An object of the present invention to provide a bone conduction earphone in which improved means are provided for holding the earphone in operative position against the user's head and in which the contacting surface is more comfortable to the user and provides efficient sound transmission.

The features of the present invention which are believed to be novel are set forth with particularity in the appended claims. This invention itself, both as to its organization and manner of operation, together with further objects and advantages thereof, may best be understood by reference to the following description taken in connection with the accompanying drawings, in which:

Figure 1 shows an assembly incorporating a hearing aid earphone which embodies the present invention.

Figure 2 shows a sectional view of the earphone of Figure 1, and,

Figure 3 shows a modification of the earphone of Figure 2.

As illustrated in Fig. 1, a casing 1 is arranged to press against a suitable portion of the user's head, for example, the mastoid bone, by mounting the composite earphone, or receiver, 2 on a suitable headband 3 having a resilient extension 4 of which a supported end is fastened to the curved head engaging resilient strap 5 of headband 3 and of which the free end is fastened to support pin 6.

With this arrangement, the pressure exerted by casing 1 of earphone 2 on the user's head is almost entirely dependent upon the resilience of extension 4, and is relatively constant, even though the resilient band 5 (arranged to contact the user's head and hold the receiver 2 in operative condition) has its opposite head engaging ends 7 and 8 stretched differently in use by persons having heads of different sizes.

Extension 4 is fastened to resilient strap 5, for example, by means of rivets 9 and may be fastened to support pin 6 by means of a screw-threaded connection (not shown) between pin 6 and the end of extension 4. A feature of the particular headband shown in Fig. 1 is that a receiver, or earphone, of the bone conduction type is held in operative position with the headband extending around over the top of the user's head

so that the user's normal activities influence in a relatively small degree the pressure of casing 1 on a suitable portion of his head. Also, this feature reduces the tendency of casing 1 to "crawl" off the mastoid bone, and controls the low frequency response by giving more uniform compliance between the user's head and casing 1.

Fig. 2 shows an enlarged view of a section through an earphone 2 of Figure 1, and as shown herein the side of casing 1 arranged to contact the user's mastoid bone or similar portion of his head is provided with a recessed portion 10 into which is cemented or bonded a layer of elastic material 11 having a concave head engaging surface 12. The nature of the elastic material 11 and the contour of its surface 12 minimizes the tendency of the casing 1 to "crawl" when in use and improves the energy transmitting contact between casing 1 and the user's head.

In the modified arrangement shown in enlarged view in Fig. 3, the side of the casing 1 arranged to contact the user's mastoid bone or similar portion of his head is provided with a recessed portion 13 enclosed by a nonporous flexible fabric material 14 which confines within said recessed portion a material 15 having the property of being solid at ordinary room temperatures but which is somewhat plastic at temperatures of about 98° Fahrenheit, the ends 16 and 17 of the fabric 14 being anchored, such as by molding said ends in the casing 1. Materials such as material 15 which is solid at room temperatures of about 70° Fahrenheit and somewhat plastic at body temperatures of the order of 98.6° Fahrenheit are plentiful and they comprise organic compounds such as greases, waxes, etc. One of the advantages residing in the use of the arrangement shown in Fig. 3 is that after fabric 14 is in resilient contact with the user's skin for a short time interval the material 15 becomes plastic, due to body heat of the user, and the contour of fabric 14 corresponds to the contour of the user's anatomy which is contacted. It is thus evident that a good contact exists between the casing proper and the user's anatomy.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. In a hearing aid unit of the bone conduction type, a casing, said casing having a recess and a surface of moldable material arranged within said recess to be molded into a concave surface in contact with skin over a user's mastoid bone.

2. In a bone conduction earphone, a casing having the contact surface with a recessed portion, a flexible nonporous thermally conducting fabric enclosing said recessed portion, and a material in said hollow portion, said material being substantially solid at temperatures in the order of 70° Fahrenheit but plastic at temperatures near body temperatures whereby contact of said fabric with a user's skin causes the material and fabric to conform in shape to that portion of the user's body which is contacted.

3. In a hearing aid unit of the bone conduction type, a casing having a recess therein, and flexible material in said recess in sufficient amount to touch a user's mastoid bone when said casing is placed thereover and of sufficient flexibility that such contact is over a substantial area.

5 4. In a hearing aid unit of the bone conduction type, a casing having a recess therein, and elastic material substantially filling said recess and having a concave outer surface to fit smoothly over a substantial area of the mastoid bone of a user.

HUGH S. KNOWLES.
